Inventor
Harold G. TOWNER

By *W. M. Roach*

Attorney

UNITED STATES PATENT OFFICE.

HAROLD G. TOWNER, OF NEW HAVEN, CONNECTICUT.

CARTRIDGE FOR PROJECTILES.

Application filed June 30, 1924. Serial No. 723,291.

(GRANTED UNDER THE ACT OF MARCH 3, 1883; 22 STAT. L. 625.)

To all whom it may concern:

Be it known that I, HAROLD G. TOWNER, a citizen of the United States, and a resident of New Haven, county of New Haven, and State of Connecticut, have invented an Improvement in Cartridges for Projectiles, of which the following is a specification.

The invention described herein may be used by the Government, or any of its officers or employees in prosecution of work for the Government, or by any other person in the United States, without payment to me of any royalty thereon, in accordance with the act of March 3, 1883.

15 The subject of this invention is a cartridge for projectiles.

In firing infantry guns especially those of the mortar type, it is customary to vary the range either by varying the angle of fire or by equipping the gun with a valve mechanism for controlling the energy of the propelling gases.

20 However, as the first method of varying the range is frequently handicapped and limited by the nature of the gun emplacement and the second method necessitates additional gun structure, I have devised a novel cartridge which will permit zone firing at low velocities for high explosive shells 25 in the same gun, which will fire armor piercing projectiles at a high velocity.

My invention consists in providing a cartridge expellable with the projectile, which may be readily removed from its container to effect the required adjustment for securing varying ranges without disturbing the setting of the gun.

To these and other ends, my invention consists in the construction, arrangement, and combination of elements, described hereinafter and pointed out in the claims forming a part of this specification.

A practical embodiment of my invention is illustrated in the accompanying drawing, in which,

Fig. 1 is a view in side elevation of a shell equipped with my improved cartridge;

Fig. 2 is a fragmentary longitudinal sectional view of the projectile;

50 Fig. 3 is a detailed sectional view of the cartridge showing the manner of disposing the powder rings; and

Fig. 4 is a sectional view on the line 4—4 of Fig. 2.

Referring to the drawings by numerals 55 of reference—

A projectile 10 may be formed at its base with a short threaded stem 11 for the reception of a cylindrical cartridge container 12. The container is provided with a plurality of apertures 13 for the purpose of 60 venting the gases generated on explosion to the breech end of the gun barrel.

The cartridge, of typical shot gun design, 65 comprises a metal base 14, formed with a milled band 15 for frictionally securing the cartridge in the container 12 and for retaining a cardboard shell 16 which is provided with perforations 17 at regular intervals about its circumference to coincide with 70 the divisions of a plurality of powder rings 18 disposed in the shell.

The projectile may be issued with a cartridge containing a complete set of powder rings which are held in place by 75 the turned in forward end 19 of the shell. If desired to secure any range less than the maximum, the cartridge may be readily removed from the container and by reason of the perforations any number of sections 80 or segments of the shell and a corresponding number of powder rings may be detached. The function of the perforations may also be obtained by reducing the thickness of the shell at intervals to form depressed rings. 85

The cartridge is provided with the usual 90 percussion cap 20 and primer 21 may be exploded either through a breech mechanism and firing pin or through an anvil fixed in the base of the gun.

When the shell is provided with a base detonating fuse, the cartridge may be inserted and carried by the fuse plug or the fuse body.

95 While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

I claim:

1. A cartridge for projectiles including

a perforated shell and a plurality of powder rings within the shell.

2. A cartridge for projectiles including a perforated shell, and a plurality of powder rings within shell, the perforations coinciding with the divisions between the powder rings.

3. A projectile, a cylindrical container removably secured to the base thereof, and a 10 cartridge carrying a propellant charge insertable in the container, said cartridge

formed with weakened annular portions to readily separate whereby to reduce the amount of the charge.

4. A projectile, a container secured to the base thereof, and a removable cartridge in said container, said cartridge formed with weakened annular portion to readily separate whereby to reduce the amount of the charge.

HAROLD G. TOWNER.
